UNITED STATES PATENT OFFICE.

CHARLES E. STORM, OF TROWBRIDGE, ILLINOIS.

LOCK FOR DIFFERENTIAL GEARS.

1,222,902.

Specification of Letters Patent. Patented Apr. 17, 1917.

Application filed December 14, 1915. Serial No. 66,777.

To all whom it may concern:

Be it known that I, CHARLES E. STORM, a citizen of the United States, residing at Trowbridge, in the county of Shelby and 5 State of Illinois, have invented certain new and useful Improvements in Locks for Differential Gears, of which the following is a specification.

My invention relates to new and useful 10 improvements in differential gear mechanism for self-propelled vehicles, the primary object of my invention being the provision of means for locking the differential mechanism, when desired, in such a manner that 15 the two live axle sections connected by it will rotate as a unit.

A still further object of my invention is 20 to provide a locking mechanism which will normally lock the differential mechanism and which will be automatically unlocked when it is desirable that such mechanism be capable of operating.

A still further object of my invention 25 consists in constructing the beveled pinions of the differential mechanism with squared hub portions against which locking rings or flanges may be moved to prevent turning of the pinions and to consequently lock the differential mechanism.

30 A still further object of my invention consists in providing a pair of locking members or rings having annular flange portions for engagement with the hubs of the pinions, the locking members being arranged 35 one at either side of the pinions and being simultaneously movable toward and away from the pinions through turning movement.

In this connection, a still further object 40 of my invention consists in the provision of means operable through turning of the steering wheel of the vehicle for simultaneously moving the rings toward and away from each other.

45 With these and other objects in view, my invention will be more fully described, illustrated in the accompanying drawings, and then specifically pointed out in the claims which are attached to and form a part of 50 this application.

In the drawings:

Figure 1 is a vertical, central, longitudinal sectional view taken through a rear axle housing and differential gear mechanism, showing my invention in use, the 55 lock being applied;

Fig. 2 is a vertical, transverse sectional view taken on the line 2-2 of Fig. 1, looking in the direction of the arrows;

Fig. 3 is a longitudinal sectional view 60 taken on the line 3-3 of Fig. 1, looking in the direction of the arrows, the differential mechanism and live axle sections being removed to more clearly disclose the locking mechanism and its actuating parts; 65

Fig. 4 is a perspective view of the locking members or rings removed from the remainder of the mechanism;

Fig. 5 is a perspective view of one of the 70 beveled pinions of the differential mechanism;

Fig. 6 is a fragmentary top plan view, showing the actuating or controlling mechanism for the lock.

Corresponding and like parts are referred to in the following description and indicated in all the views of the drawings 75 by the same reference characters.

In the drawings, reference being had particularly to Fig. 1, 10 indicates sections of 80 the customary rear axle housing, the adjacent ends of these sections being enlarged to engage and form portions of the differential housing 11 which has flanges to receive bolts 12 by means of which it is connected to the axle housing sections. As the specific construction of this rear axle and differential housing forms no part of 85 my present invention, further explanation thereof is believed to be unnecessary. 90

The rear axle housing sections 10, adjacent their inner ends, are formed with aligned bearings 13 to rotatably receive the live axle sections 14 having the squared inner terminals 15 which are spaced from 95 each other and which carry the beveled gears 16 of the differential mechanism. The live axle sections 14, just outside of the beveled gears 16, carry any suitable type of bearings 17 to rotatably receive collars 18 100 having radially and inwardly extending arcuate arms 19 which are secured by bolts or other suitable fastening means to the opposite sides of the body portion of the beveled drive gear 20 of the differential 105 mechanism. This beveled drive gear 20 is located between the beveled gears 16 and concentrically disposed with respect to such gears and the axle sections 14. The drive gear 20 is also provided with bearings to 110 receive the stub shafts 21 which carry the beveled pinions 22, each of which meshes

with both of the beveled gears 16. These beveled pinions, beyond the periphery of the gears 16, are formed with squared hub portions 23 which are also disposed beyond 5 the arms 19, which, together with the collars 18 and driving gear 20, constitute the driving cage of my differential mechanism.

The locking mechanism proper for the above described differential mechanism consists primarily of a pair of locking members or rings, indicated as a whole by the numerals 24 and 25. Each of these locking members or rings includes an annular body portion 26 substantially equal in external 15 diameter to the internal diameter of the differential mechanism housing 11 in which it is mounted for turning movement. Each body portion 26 is provided with an inwardly directed annular locking flange 27 20 of such size that when the locking members are moved inwardly, the flanges 27 will engage the hub portions 23 of the pinions 22. As shown in Fig. 1, the locking member 24 is mounted at one side of the differential 25 mechanism, while the locking member 25 is mounted at the other side.

The body portions 26 of both locking members are formed with spaced longitudinally extending slots 28 and pins 29 are 30 passed through these slots and into the wall of the housing 11. The slots of one locking member are reversely inclined with respect to those of the other and it will, therefore, be clear that simultaneous turning movement of the locking members in the same direction will cause them to simultaneously move toward or away from each other, according to the direction in which they are turned. Of course, when they have turned 35 in such a manner as to move toward each other, their locking portions 27 will be moved into simultaneous engagement with the opposite flattened faces of the hub 23 of the beveled pinions 22 to lock the differential 40 gearing in such a manner that the live axle sections will be driven together as a unit.

In order to provide means for simultaneously turning the locking members 24 and 25, the upper wall of the housing 11 is 45 formed with bearings 30 to receive rotatable shafts 31 provided at their outer ends with crank arms 32 and at their inner ends with eccentrically mounted pinions 33. These pinions mesh with rack teeth 34 formed in 50 the outer edges of the body portions of the locking members 24 and 25, respectively, and the eccentric mounting of the pinions is such that they will constantly engage with the rack teeth during turning of the locking 55 member and consequent movement of such members toward and away from the shafts 31. It will, of course, be clear that if the shafts 31 are simultaneously but oppositely rotated, the locking members will be simultaneously turned in the same direction.

Any suitable means for properly rotating the shafts 31 to actuate their pinions may be provided and I do not wish to limit myself to any specific mechanism for this purpose. I prefer, however, that these locking members shall normally be held in locking engagement with the pinions and moved out of such engagement only when the vehicle is traveling in other than a straight line. For this reason I prefer that the release of the locking members be effected through suitable connections between the crank arms 32 of the shafts 31 and some portion of the steering mechanism of the vehicle. For instance, in Fig. 6, I have illustrated one form of mechanism by means of which the lock may be controlled by movement of the steering column 35 of the vehicle. In this structure, a bell crank lever 36 is fixed to the steering column with its 60 diverging arms extending rearwardly. Links 37 are pivotally connected to the free ends of the arms of the bell crank lever 36 and are formed with slots 38 to slidably receive a pin coupling 39 carried by a connecting rod 40. The opposite end of this rod terminates in a head 41 and links 42 pivotally connect this head with the free ends of the crank arms 32. A spring 43 is also connected at one end to the head 41 and at its 65 other end to any fixed object, such as the housing 11 of the differential mechanism.

As will be apparent from an inspection of Fig. 6, this spring 43 tends at all times to hold the crank arms 32 as far to the rear as permitted by the links and connecting rod connections between them and the bell crank lever carried by the steering column. It will be understood that in its normal position, the steering column or post is in the 70 position which it occupies when the vehicle is going straight ahead and the crank arms 32 are in the position which they occupy when the locking members are in active engagement with the hubs of the pinions 22. 75 It will also be apparent that turning of the steering post in either direction, to cause turning of the vehicle, will pull upon the connecting rod 40 and cause simultaneous but opposite turning of the crank arms 32 80 and, consequently, of the pinions 33 to rotate both locking rings in the same direction and, consequently, simultaneously move them out of engagement with the pinion hubs.

Although I have illustrated and described my invention in all its details, it will of course be understood that I do not wish to limit myself to the specific construction disclosed, as any changes, within the scope of 85 the appended claims, may be made if deemed advisable.

Having thus described the invention, what is claimed as new is:

1. The combination with a differential 90

gearing including axle section receiving gears and pinions meshing with the gears and having squared hub portions, of means movable into engagement with the squared hub portions of the pinions to lock them against turning movement.

2. The combination with a differential gearing including axle section receiving gears and pinions meshing with the gears 10 and having squared hub portions, of means movable into engagement with the squared hub portions of the pinions to lock them against turning movement, said means including a locking member movable toward 15 and away from the pinions, and a locking flange carried by the member for simultaneous engagement with the hub portions of the pinions.

3. The combination with a differential 20 gearing including axle section receiving gears and pinions meshing with the gears and having squared hub portions, of means movable into engagement with the squared hub portions of the pinions to lock them 25 against turning movement, said means including a locking member movable toward and away from the pinions, a locking flange carried by the member for simultaneous engagement with the hub portions of the 30 pinions, and means for controlling the movement of the locking member.

4. The combination with a differential gearing including axle section receiving gears and pinions meshing with the gears 35 and having angularly faced hub portions, of locking members disposed at either side of the pinions and movable into and out of engagement with the hub portions thereof.

5. The combination with a differential 40 gearing including axle section receiving gears and pinions meshing with the gears and having angularly faced hub portions, of locking members disposed at either side of the pinions and movable into and out of engagement with the hub portions thereof, and a spring constantly tending to hold the locking members in engagement with the hubs of the pinions.

6. The combination with a housing and a 50 differential gearing inclosed in the housing and including axle section receiving gears and pinions meshing with the gears and having squared hub portions, of annular locking members mounted for turning movement in 55 the housing and surrounding the differential mechanism therein, and means extending into the housing for moving the locking members toward and away from the pinions.

7. The combination with a housing and a 60 differential gearing inclosed in the housing and including axle section receiving gears and pinions meshing with the gears and having squared hub portions, of annular locking members mounted for turning movement 65 about the axis of the differential and within

the housing, said members being formed with diagonally disposed slots, the slots in one being reversely disposed to those in the other, pins extending from the housing through the slots, whereby corresponding 70 turning of the locking members will move them both toward or away from the pinions, and means for so turning the locking members.

8. The combination with a housing and a 75 differential gearing inclosed in the housing and including axle section receiving gears and pinions meshing with the gears and having squared hub portions, of annular locking members mounted for turning movement 80 about the axis of the differential and within the housing, said members being formed with diagonally disposed slots, the slots in one being reversely disposed to those in the other, pins extending from the housing 85 through the slots, whereby corresponding turning of the locking members will move them both toward or away from the pinions, and means for so turning the locking members, said means including rack teeth formed 90 upon the locking members, and reversely rotatable gears meshing with the racks.

9. The combination with a housing and a 95 differential gearing inclosed in the housing and including axle section receiving gears 100 and pinions meshing with the gears and having squared hub portions, of annular locking members mounted for turning movement about the axis of the differential and within the housing, said members being formed with diagonally disposed slots, the slots in one being reversely inclined to those in the other, pins extending from the housing 105 through the slots, whereby corresponding turning of the locking members will move them both toward or away from the pinions, and means for so turning the locking members, said means including rack teeth formed on the outer edges of the locking members, eccentrically mounted gears meshing with 110 the racks, shafts for the gears, means including a rod for reversely rotating the shafts, and a spring connected to the rod normally holding the gears in such position as to hold the locking members in engagement with 115 the pinions.

10. The combination with a differential 120 gearing including axle section receiving gears and pinions meshing with the gears and having squared hub portions, of locking members mounted for turning movement, means for simultaneously turning the locking members, and means whereby such turning of the locking members will move them into or out of engagement with the hub 125 portions of the pinions.

11. The combination with a differential 130 gearing including axle section receiving gears and pinions meshing with the gears and having squared hub portions, of lock-

ing members mounted for turning movement, means for simultaneously turning the locking members, and means whereby such turning of the locking members will move them into and out of engagement with the hub portions of the pinions, such means normally holding the locking members in engagement with the pinions.

12. The combination with a motor propelled vehicle having a rotatable steering post, of a differential mechanism including axle section receiving gears and pinions meshing with the gears and having squared hub portions, locking rings movable toward and away from the squared hub portions, rotatably mounted shafts, means operable upon reverse rotation of the shafts for simultaneously moving the locking rings toward and away from the pinions, crank arms carried by the shafts, a connecting rod, links pivotally connecting the free ends of the

crank arms with one end of the rod, a spring fixed at one end and connected at the other to the rod to normally hold the latter in one position, a bell crank lever having diverging arms fixed to the steering post, links pivoted to the free ends of the arms of the lever and having their free ends slotted, and a pin carried by the connecting rod and engaging in the slots of the links, whereby turning of the post in either direction will pull forwardly upon the rod against the tension of the spring.

13. The combination with a differential gearing including axle section receiving gears and pinions meshing with the gears, of a locking ring encircling an axle section receiving gear and movable into direct frictional engagement with all the pinions to hold them against turning movement.

In testimony whereof, I affix my signature.
CHARLES E. STORM. [L.S.]
